United States Patent Office.

W. W. SUTLIFF, OF TOWN LINE, PENNSYLVANIA.

Letters Patent No. 75,999, dated March 24, 1868.

IMPROVEMENT IN CARRIAGE-SPRINGS.

The Schedule referred to in these Letters Patent and making part of the same.

TO ALL WHOM IT MAY CONCERN:

Be it known that I, W. W. SUTLIFF, of Town Line, in the county of Luzerne, and State of Pennsylvania, have invented certain new and useful Improvements in Carriage-Springs; and I do hereby declare that the following is a full, clear, and exact description thereof, reference being had to the accompanying drawings, and to the letters of reference marked thereon, which form a part of this specification, in which—

Figure 1 represents a side elevation of a vehicle with my invention attached, and

Figure 2 a plan of the same, with the body removed.

The nature of this invention consists in the employment of four bars, which act in the capacity of springs when said bars or springs are arranged in combination with such other devices as will be hereinafter described.

The advantages of my method of forming springs for vehicles are, first, its economy; second, its simplicity, and consequent ease with which it can be made, even by the most ordinary mechanic.

To enable others skilled in the art to make and use my invention, I will now describe its construction.

A A represent the axles, upon which are the wheels B B. C designates a bolster, secured to the axle B, by means of a king-bolt, in the usual manner. Upon said bolster rest the front ends of the perches or rods D D, the rear ends of said perches resting upon the other axle, B. F F indicate four bars or rods, to act in the capacity of springs, which may be bevelled at their inner ends, to allow them to rest upon the perches at the desired inclination. These springs are provided with metal plates or strips, a a, on their upper sides. Said plates are curved, or formed, with eyes at their lower ends, so that the springs may be secured to the rods or perches D D, in a manner hereinafter set forth. E E designate two clips, which pass around the perches or rods D D. e e are bolts, furnished with nuts, which pass from side to side of the clips E E, through the eyes or curved ends of the plates, thus securing the bars or springs to the perches D D. G G represent two adjustable cross-bars, the ends of which rest on the rods or perches D D, as seen in fig. 1. The object of these bars is to raise and support the springs at any desired angle or inclination. These bars are provided with two screw-rods, K K, said rods being furnished with nuts, by means of which the bars G G may be adjusted and held in position. I I designate four screw-bolts, also provided with nuts. Said bolts are inserted in holes in the springs and rods or perches, to keep the springs in place. J J are cross-bars, attached to the outer ends of the bars or springs. Said bars are furnished with staples, e e. h h represent hooks, secured to the ends of the body of the vehicle, and which are fitted in the staples e e. m designates the body of the vehicle, upon which is placed the seat b.

Thus it will be seen, from the peculiar construction of my invention, that I derive spring from both the perches and springs.

Having thus described my invention, what I claim as new, and desire to secure by Letters Patent, is—

1. Spring-bars F F, provided with metal plates a a, perches D D, arranged in combination with clips E E and bolts e e, as and for the purpose set forth.
2. The adjustable cross-bars G G, in combination with spring-bars F F.
3. The employment of the screw-rods K K, in combination with adjustable cross-bars G G and spring-bars F F, substantially as and for the purpose specified.

In testimony that I claim the foregoing as my own, I affix my signature in presence of two witnesses.

Witnesses:

M. W. MILLARD,
J. D. WARNER.
